UNITED STATES PATENT OFFICE

STANLEY C. DREHER, OF CINCINNATI, OHIO, ASSIGNOR TO THE NEWMAN MANUFACTURING COMPANY, OF NORWOOD, OHIO, A CORPORATION OF OHIO

AWNING INCLOSURE

Application filed October 30, 1929. Serial No. 403,607.

My invention relates to awnings and their mountings, and its object is to inclose the awning when retracted or rolled up, to afford a more slighted appearance to the building structure equipped with the awning, as well as to protect the awning from the weather when not in use. A further object is to make the opening and closing of the inclosure independent of the attention of the 10 operator who extends or retracts the awning. Other objects will appear in the course of the following description.

I accomplish the above objects by the device illustrated, for example, in the accompanying drawing, in which—

The figure is a front-to-rear vertical section of the device.

The awning pole 1, to which the lower end of the awning 2 is attached, is supported at 20 its ends by arms 3, the upper ends of which curve inwardly and are fixed to the pole 1, while the lower ends, not shown, are understood as being pivoted to a post or jamb 4 at the respective side of the door or window 25 or the like which is shaded by the awning.

The lintel structure 7 supported by these posts or jambs 4 or by the building wall comprises a channel 8, which, for the purposes of my invention, is set back from the face of 30 the building, and the forwardly extending bottom plate 9 and top plate 10 secured to the respective flanges of the channel 8 and suitably braced by brackets 8' the upper ones of which also support at the front a fixed 35 depending wall 11 to which the cornice 12 is attached.

The roller 13 onto which the awning 2 is wound is journaled in the ends of the inclosure, and, at one end, in a gear box 14 40 mounted on the channel 8 and understood to contain suitable gearing operatively connecting the roller 13 with the upright shaft 15 extending down through the bottom plate 9, understood to connect this shaft, with the usual ratchet device, not shown, but understood as being mounted on the face of the adjacent jamb or post within easy reach of the operator.

All of the foregoing building and awning 50 structure is well known in the art, and the

partial illustration and brief description are deemed sufficient for a full understanding of my invention as related thereto. Such prior structures have been provided with the winding roller 13 set back in an inclosure, to draw 55 the awning 2 and its pole 1 inside the inclosure; but, so far as I am aware, the front of the inclosure always has been left open, with the awning and pole visible, detracting from the appearance of the store front or 60 the like, as well as leaving the awning, when rolled up therein, exposed to the weather as well as to dust and dirt which collects in the inclosure and upon the awning. The result is that the awning not only unduly is deteriorated, but becomes dirty and unsightly; 65 and, unless excessive deterioration and soiling is allowed, the awning must be taken down at the beginning of cold weather and then put up again for the following warm 70 season.

In my invention, the shutter 17 is connected by a hinge 18 to the lower edge of the upper front wall 11 of the inclosure, and the lower edge part of the shutter bears against 75 a stop strip 19 on the upper edge of and set back from the face of a lower fixed wall 20 at the front of the bottom plate 9 of the inclosure. This lower edge part preferably is curved outward, forming a flange 21 with 80 its downwardly and inwardly presented side convex. To allow the shutter 17 to close when the arms 3 are up, with their end parts curving into the inclosure, the shutter is provided with slots 22, opening through its 85 lower edge.

The hinge 18 preferably is made up of an outer half tubular part 23 fixed to the upper edge of the shutter 17 with its open side outward, and having an upstanding flange 24 to 90 which the round bar 25 has its upstanding flange 26 fixed, and an inner half tubular member 27 opening upwardly and hooking around the bar 25, with its outer edge fixed to the upper front wall 11 of the inclosure. 95 The round bar 25 thus turns in the inner member 27, with the bar flange 26 swinging down and inward toward the edge of the member 27 as the shutter 17 swings open upwardly. This hinge structure extends un- 100

interruptedly from end to end of the shutter, and is practically weather proof.

At the ends of the inclosure, alongside the awning 2, weights 28 are fixed to the shutter 17, each comprising a saddle part 29 straddling the hinge 18 and screwed to the shutter 17 below the pivotal axis thereof and to the upstanding flanges 24 and 26 thereof; and each comprising a flange part 30 extending down when the shutter is closed, with its widened lower edge part 31 extending backward over the awning pole 1 and down behind the pole where it engages the rear side of the pole. At intervals along the shutter 17 smaller weights 32 are fixed thereto, extending up therefrom when the shutter is closed, as does the main heavy part of each end weight 28; the latter having its rear edge curved to clear the gear box 14, and the lower end of its flange edge part 31 being short enough to clear the top of the stop strip 19 as the shutter 17 swings open upwardly.

It will be understood that, upon completion of the operation of winding up the awning, the ratchet device before alluded to holds the roller 13 from turning and the awning 2 thereon holds the pole 1 and arms 3 up, and this pole 1, engaging the weight flange parts 31 as shown, holds the weights 28 up and the shutter 17 closed and holding its small weights 32 up as shown. But as soon as the ratchet device is released to lower the awning 2, the weights 32 and 28 act, through the engagement of the weight flanges with the pole 1, to push the latter with its arms 3 outward and downward, and to swing the shutter 17 outward and upward. These weights 28 and 32 are so designed and proportioned, and so mounted on the shutter 17, that when thus released they will hold the lower edge part 21 of the shutter with its convex side very close to or upon the awning 2 unwound thereunder; but, if actually touching the awning, touching it very lightly. The result of this convexity of the edge part 21 of the shutter, and this very light bearing, if any, on the awning, is to avoid wearing the top surface of the awning 2, preserving the hard, smooth, water shedding surface of the awning; yet the space above the awning, at the front of the inclosure, is closed in such degree, when the awning is extended, that there is a substantially full protection of the working parts inside the inclosure, against the weather and dust and dirt, at all times, whether the awning is extended for use or retracted into the inclosure.

Upon retracting the awning, the pole 1 first passes under the lower part of the shutter 17, which is lying out over the awning, and then engages the flange parts 31 of the weights 28, raising them and drawing the shutter 17 to closed position again, with the

weights 28 and 32 extending upward. It thus will be seen that the operator of the awning need pay no attention to the opening or closing of the shutter 17, and my device is automatic, with no hindrance to the operator except the inappreciable extra exertion required to overcome the weights 28 and 32 in the last stages of retraction, and the closing of the shutter, and consequent protection afforded, is not dependent upon the memory of the operator.

In existing structures, where the lintel beam, such as the channel 8, is set out at or near the face of the building, an inclosure may be specially provided and fixed in front of the lintel, to overhang the store front, door, window, or the like, and provided with my improvement.

As disclosed, the device is designed for a part of an all metal building structure, such as the finer store fronts and the like, but it will be understood that wood, or other materials other than metal may be used, in which case the arrangement of certain parts may differ from that herein set forth, or other modifications may occur, either with or without modification of material. Therefore, while I have rather specifically described and illustrated certain preferred examples of my invention, I do not wish to be understood as being limited thereto, but what I claim as new and desire to secure by Letters Patent is:

1. An awning inclosure having an opening, an awning mounted in said inclosure for extension and retraction through said opening, a shutter having a hinge above said opening on which it swings down across said opening upon retraction of said awning, and to swing open upwardly upon extension of said awning and a weight on said shutter, extending above said hinge.

2. An awning inclosure having an opening, an awning mounted in said inclosure for extension and retraction through said opening, an arm mounted outside said inclosure to support said awning, extending through said opening when said awning is retracted, and a shutter for said opening having a recess admitting said arm when said shutter is closed.

3. An awning inclosure having an opening, an awning in said inclosure, a pole on said awning, said pole and said awning being adapted to be extended and retracted through said opening, a shutter mounted on said enclosure to cover said opening when said pole and awning are retracted into said inclosure, and a weight acting on said pole and said shutter to extend said awning and open said shutter simultaneously.

4. An awning inclosure having an opening, an awning to be extended and retracted through said opening, a shutter to cover said opening when said awning has been retracted, and a weight having an opening op-

eration on said shutter, held up by the retracted awning, and released to open said shutter upon extension of said awning.

5. An awning inclosure having an opening, an awning structure comprising an awning to be extended or retracted through said opening, a shutter to cover said opening when said awning has been retracted, and a weight connected to said shutter for opening said shutter and having an extension engaged by a part of said awning structure when said awning is retracted, whereby said weight is raised restrained by the retracted awning and is released for opening said shutter when said awning is extended.

10 6. An awning inclosure having an opening, an awning structure mounted in said inclosure for extension and retraction through said opening, a shutter for said opening, a weight operatively related to said shutter to open said shutter, and means whereby a part of said awning structure, upon retraction, closes said shutter.

15 7. An awning inclosure having an opening, an awning structure mounted in said inclosure for extension and retraction through said opening, a shutter for said opening, a hinge for said shutter, a weight attached to said shutter and extending above said hinge when said shutter is closed, to open said shutter, and means whereby a part of said awning structure, upon retraction, closes said shutter.

20 8. An awning inclosure having an opening, an awning in said inclosure, a pole on said awning, said pole and said awning being adapted to be extended and retracted through said opening, a shutter for said closure, a hinge for said shutter, a weight attached to said shutter and extending above said hinge, to open said shutter, and an extension on said weight to engage said pole whereby said pole, upon retraction, closes said shutter.

25 9. An awning inclosure having an opening for extension of the awning, and having a space above said opening, a shutter for said opening, and a weight on said shutter extending into said space when said shutter is closed.

30 10. An awning inclosure having an opening for extension of the awning, a shutter for said opening, and a weight connected to said shutter, disposed to open said shutter.

55 STANLEY C. DREHER.
